UNITED STATES PATENT OFFICE.

MAXWELL ALPERN, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

TWYER FOR STOKERS.

1,123,063.

Specification of Letters Patent.

Patented Dec. 29, 1914.

Application filed February 25, 1914. Serial No. 820,902.

To all whom it may concern:

Be it known that I, MAXWELL ALPERN, a citizen of the United States, residing in Philadelphia, Pennsylvania, have invented 5 certain improvements in Twyers for Stokers, of which the following is a specification. One object of my invention is to provide a novel form of twyer particularly designed for use with stokers of the inclined under 10 feed type, the construction being such that the air is discharged into the fuel not only straight in front of the twyer but at the sides thereof and if desired from the top also, with a view to obtaining the most effi- 15 cient and economical burning of said fuel.

I further desire to provide a twyer having the above noted characteristics, which in addition shall be of such construction as to be conveniently applied to or removed from 20 the stoker of which it forms a part, the arrangement of parts being such as to facilitate the removal or insertion of any particular twyer.

These objects and other advantageous 25 ends I secure as hereinafter set forth, reference being had to the accompanying drawings, in which,

Figure 1 is a perspective view illustrating a twyer constructed according to my invention; Fig. 2 is a plan of the twyer shown in Fig. 1; Fig. 3 is a longitudinal section on the line *a—a*, Fig. 2; Figs. 4 and 5 are respectively a plan and a side elevation of a 30 unmodified form of twyer; Figs. 6 and 8 are 35 plans of two other forms of tuyers constructed according to my invention, and Figs. 7 and 9 are respectively side elevations of the tuyers shown in Figs. 6 and 8.

Referring to Figs. 1 to 3 inclusive of the 40 above drawings, the twyer therein shown consists of a body portion in the form of a flat relatively thin plate pointed at its front end and adjacent its straight rear edge provided with an opening or hole 2 for the 45 reception of a similarly formed projection 3 belonging to a similarly formed twyer immediately adjacent it in the stoker. This projection 3 extends from the upper surface of a relatively narrow elongated raised portion 4 extending rearwardly from the point 50 end of the twyer and disposed symmetrically on both sides of the central vertical plane of the body plate 1, there being on each side of this central projection, two inwardly extending portions 5 which are also

raised above the top surface of the body plate 1 in such manner that they coöperate with the central portion 4 to form air passages having outlets terminating on the inclined sides of the pointed end of the twyer. 60 Each of these air passages, however, is divided at its outer end by another raised portion 6 so as to form two air outlets 7 and 8 of which the former has its side walls so disposed that the air is discharged in a direction substantially at right angles to the longitudinal center line of the twyer, while each of the latter outlets 8 is designed to discharge the air forwardly parallel to said center line. It is to be noted that all of the 70 raised portions 4, 5, and 6 extend to the same height above the top surface or plane of the twyer body 1, the interlocking projections 3, however, extending beyond the plane of the top surfaces of these portions at the rear 75 end of the portion 4, while at the forward end of said portion I provide a lug 9 of L-shaped section designed to fit into a hole 10 formed in what is the under surface of the twyer shown in Fig. 1. This hole is forwardly under-cut as indicated at 11 to receive the projecting lip 12 of said lug, so that, as indicated in dotted lines in Fig. 3, the lug 9 extends into the hole 10 of the 80 twyer next below that shown in full lines, 85 while the projection 3 similarly extends into the opening 2 of the same twyer. By this means the units in each inclined column or series of tuyers are locked together and since the twyer which lies immediately below that shown in Fig. 1 is spaced away 90 from its body by the raised portions 4, 5 and 6, the air from the wind box at the rear of said series flows between the bodies of each pair of adjacent tuyers, escaping from 95 each side of the point of each twyer in two currents substantially at right angles to each other.

It is to be noted that the width of the passages 7 is substantially three times greater 100 than that of the passages 8 and they consequently deliver approximately three times as much air laterally from the tuyers in lines substantially at right angles to the longitudinal lines thereof. Obviously, if the 105 tuyers are built up in a number of series whose units lie with their bodies uppermost and the projecting portions 4, 5 and 6 extending downwardly on to the plane surface of the next lower twyer, the air delivered 110

from the openings 7 and 8 necessarily flows at the point of delivery in substantially horizontal lines.

Adjacent the walls of the furnace the twyers of the outer series preferably have the forms indicated in Figs. 4 and 5, the twyer body having the general outline indicated at 1^a and formed with one of its sides substantially at right angles to its rear edge, 10 while its other side for about half of its length is inclined, as indicated at 13. As before there is a relatively large air passage 7 which opens on the inclined side and which is defined by the surface of the body 1^a, by a portion of the edge of a raised portion 4^a, and by a second raised portion 5^a. The air passage 8, however, is omitted from this side of the twyer, although the opposite side thereof has an air passage 8^a indicated 15 in dotted lines in Fig. 4, whose sides are defined by the second elongated side of the projecting portion 4^a and by an edge flange or projection 14 extending along that side of the twyer at right angles to its rear edge. 20 The front end of each twyer is substantially parallel to its rear edge and the air passage 8^a opens thereon so that it discharges air at right angles to the passage 7. As before, the body of the twyer adjacent its rear edge 25 is provided with an opening 2 and there is a similarly formed lug 3 extending from the rear end of the raised portion 4^a. Adjacent the center of this portion is the opening 10, which as before is under-cut at 11 for the 30 reception of the L-shaped lug of the next higher twyer. In some cases the tuyers of the side series may be made as indicated in Figs. 6 and 7, the construction being substantially identical with that of Figs. 4 and 35 40 except that the air passage 8^b is relatively narrow, and the side wall 14^a instead of being carried around at the front end of the twyer so as to limit the width of the outlet of the air passage, is substantially parallel 45 50 sided for the greater part of its length. In this case the opening 2 and the lug 3 instead of lying in the longitudinal line passing through the opening 10 and the L-shaped lug 9, lie in a line to one side of but parallel to this latter line.

In some cases the twyer may be made with a plurality of forwardly directed openings and its air passages, instead of having their side walls formed on sweeping and 55 relatively gentle curves, may be made of a rather more angular outline. The twyer body has the same general outline as in Figs. 1 to 3 but its side raised portions 5^c terminate adjacent the end of the sides defining the pointed end of the twyer, extending 60 inwardly therefrom toward each other so as to provide a central air opening whose width is about one-third the width of the twyer. Each of the inclined front edges of 65 the twyer has two raised portions 15 and

16 spaced apart to provide an air discharge opening 17 between them, the former of each of these portions being in turn spaced away from one of the longitudinally extending strips 18 lying substantially parallel to but on opposite sides of the center line of the twyer body, each of said strips terminating a short distance from the inwardly projecting ends 19 respectively of the side portion 5^c. In this case the top surface of 75 the body 1^a has an elongated centrally placed rectangular lug 20, extending rearwardly from a point to the rear of the pointed end of the twyer, and so designed as to fit between the two projecting portions 18 80 of the twyer immediately above it. Somewhat to the rear of the center of the twyer body is a downwardly projecting lug designed to fit into the similarly formed opening 2 immediately adjacent the rear edge of 85 the twyer lying immediately under it. With this construction the air passes from the wind box to the rear of the tuyers between the bodies of each pair of adjacent tuyers, and thence flows between the parts 19 and 90 the elongated projections 18, being finally delivered from the twyer in three currents or streams, of which those delivered from the openings 21 and 17 are substantially at 95 right angles to that delivered from the opening 22.

The particular advantage of the above noted construction resides in the highly efficient disposition of air in the body of fuel which results from its delivery in the 100 streams substantially at right angles to each other, for each of these streams flowing from the openings 8 or 17 and 21 are in the general direction of movement of the fuel, while those issuing from the openings 22 are substantially at right angles to such direction of movement and to a greater or less degree extend into the mass of fuel as it is delivered from the adjacent retorts.

I claim:—

1. A stoker twyer consisting of a relatively flat plate having a pointed end; with raised portions projecting from one face of said plate, one of said portions extending rearwardly from the pointed end of the plate, another extending along one side thereof, and a third projection extending along the side of the pointed end away from each of the other raised portions to define air passages discharging in lines substantially at right angles to each other.

2. The combination in a twyer of a relatively flat plate having two inclined sides forming a pointed end; with a plurality of raised portions projecting from one face of said plate to substantially the same level, two of said projecting portions being respectively at opposite sides of the rear portion of the plate, another portion extending rearwardly from the front of the pointed

end; and two others of the said portions lying respectively along the inclined sides of the end in positions to coöperate with the other projecting portions to define air passages, of which those on each side of the center line of the twyer are formed to discharge in lines substantially at right angles to each other.

3. A stoker twyer consisting of a plate 10 having a substantially rectangular body portion and a triangular end; with raised portions projecting from one face of said plate of which one extends rearwardly from the apex of said end, two others lie adjacent

opposite sides of the body and two other 15 portions are respectively on opposite sides of the triangular end, being spaced away from the other raised portions to form two sets of air passages of which those on each side discharge in lines substantially at right 20 angles to each other.

In testimony whereof, I have signed my name to this specification, in the presence of two subscribing witnesses.

MAXWELL ALPERN.
